UNITED STATES PATENT OFFICE

156,206

DESIGN FOR AN INTERIOR WALL PANEL

William Chavalas, Los Angeles, Calif., assignor to
Fox West Coast Theatres Corporation, Los Angeles, Calif., a corporation of Delaware

Application August 12, 1946, Serial No. 132,458

Term of patent 14 years

(Cl. D68—1)

To all whom it may concern:

Be it known that I, William Chavalas, a citizen of the United States, residing in Los Angeles, in the county of Los Angeles and State of California, have invented a new, original, and ornamental Design for an Interior Wall Panel, of which the following is a specification, reference being had to the accompanying drawing, forming a part thereof.

Fig. 1 is a front elevational view of an interior wall panel showing my new design, the rear side being plain;

Fig. 2 is a top edge view; and

Fig. 3 is a section of the panel taken between lines 3—3 of Fig. 1 on an enlarged scale.

I claim:

The ornamental design for an interior wall panel, as shown.

WILLIAM CHAVALAS.
